UNITED STATES PATENT OFFICE.

LEWIS E. CURTIS, OF CHICAGO, ILLINOIS, ASSIGNOR TO BRECKENRIDGE JONES, TRUSTEE, OF ST. LOUIS, MISSOURI.

PROCESS OF MANUFACTURING EXPANDED METAL.

No. 897,879.

Specification of Letters Patent.

Patented Sept. 8, 1908.

Application filed September 4, 1906. Serial No. 333,092.

To all whom it may concern:

Be it known that I, LEWIS E. CURTIS, a citizen of the United States, residing in Chicago, in the county of Cook and State of Illinois, have invented a new and useful Improvement in Processes of Manufacturing Expanded Metal, of which the following is a specification.

It has been customary for some time in the manufacture of expanded metal to simultaneously slit and bend portions of a plate or sheet of metal in such manner as to stretch or elongate the bars connecting the slit portions and body of the sheet or plate, and then to simultaneously slit and bend in places alternate to the first mentioned portions, thus producing a finished expanded metal sheet of the same length as the original sheet. This stretching of the strands or bars stiffens the expanded sheet and gives it increased strength over what it would possess if expanded without any stretching of the bars or strands. The results attained are beneficial, but the method of manufacture is slow.

My object in the present invention is to obtain the same benefit from the stretching of the metal as is obtained in the process above mentioned, in a process of manufacture such as that set forth in the patent to me of August 1st, 1905, No. 796,402. This process is adapted to manufacture expanded metal at a very greatly increased rate over the methods heretofore used but operates to materially shorten the sheet.

In devising this invention I have sought to cause the stretching and hardening or stiffening of the metal without any lessening in the speed of the manufacture, so that the capacity of the apparatus will remain unaffected by the present invention.

The invention, briefly stated, consists in subjecting the sheets after they are slit and before they are opened, to a heavy pressure between cold rolls such as will cause the required hardening and stiffening of the metal and such a lengthening of the sheets as will compensate for the shortening thereof which takes place when they are opened.

In the accompanying drawing, I show at Figure 1 a section, omitting details, of the apparatus used by me in the practice of my invention. At Fig. 2 I show a plan of the sheet before it is cut or slit, and at Fig. 3 a like plan after the sheet is cut or slit. At Fig. 4 I show an edge view of the same. Fig. 5 is

a plan view of the sheet after it has been stretched, and Fig. 6 is an edge view of the same. Fig. 7 shows a portion of the expanded sheet.

In said drawing 10 represents the sheet undergoing the operation of the apparatus, and 11 11 represents the slitting rolls, such, for instance, as are patented to me in Patent No. 671,915 of April 9th. 1901, by which the sheet is first operated upon. These rolls deliver the sheet to a pair of pressure rolls 12 12 adapted to exert such pressure upon the sheet as will harden and stiffen the metal and lengthen it to the extent desired and produce the added rigidity and strength mentioned. Figs. 5 and 6 show approximately the amount of lengthening or stretching to which the sheet may be subjected. From these pressure rolls the sheet passes to the expanding devices 13 13 which are preferably of the kind set forth in my said Patent No. 796,402. Any other construction of suitable expanding mechanism may, however, be substituted for that shown. The resulting product will be such as is illustrated, and found to possess the increased rigidity and strength which are desired.

I claim:

1. The improvement in the process of manufacturing expanded metal, consisting in first slitting the sheet, then subjecting it to a swaging pressure between rolls, and then opening the sheet.

2. The process of making expanded metal, consisting in first slitting the sheet then rolling it with a swaging pressure, and then opening it, substantially as set forth.

3. The process of making expanded metal, consisting in first slitting the sheet, then rolling it in the direction of the slits with a swaging pressure, and then opening it, substantially as specified.

4. The improvement in the art or process of manufacturing expanded metal consisting in subjecting the sheet after it is slit and before it is opened, to a hardening operation.

5. The improvement in the art or process of manufacturing expanded sheet metal consisting in subjecting the sheet after it is slit and before it is opened to a hardening and lengthening operation.

LEWIS E. CURTIS.
